UNITED STATES PATENT OFFICE.

ANDREW R. PETERSON, OF FARGO, NORTH DAKOTA.

SHOCK-FORMER.

1,348,046.

Specification of Letters Patent. Patented July 27, 1920.

Application filed June 13, 1919. Serial No. 303,854.

To all whom it may concern:

Be it known that I, ANDREW R. PETERSON, a citizen of the United States, residing at Fargo, in the county of Cass and State of North Dakota, have invented new and useful Improvements in Shock-Formers, of which the following is a specification.

This invention comprehends the provision of a grain binder attachment, and in the nature of a shock former designed to receive the sheaves from the binder in a horizontal position to form the shock, and capable of being manipulated by one standing upon the platform of the attachment or from the driver's seat of the binder, to arrange the shock in an upright position upon the ground.

The nature and advantages of the invention will be better understood when the following detailed description is taken in connection with the accompanying drawing, the invention residing in the construction, combination and arrangement of parts as claimed.

25 In the drawings forming part of this specification, like numerals of reference indicate similar parts in the several views and wherein:

Figure 1 is a plan view of the attachment showing the normal position of the parts for receiving the sheaves from the binder.

Fig. 2 is a similar view showing the initial adjusted position of parts for arranging the shock vertically from its horizontal position.

Fig. 3 is a similar view showing the final adjustment of the parts to release the shock from the former.

Fig. 4 is a side elevation of the attachment.

Fig. 5 is a sectional view taken on line 5-5 of Fig. 4.

Fig. 6 is an end elevation showing the parts in the same relative position as illustrated in Fig. 2.

The attachment forming the subject matter of my invention embodies a frame indicated generally at A and including among other features the spaced parallel side members 10. A platform 12 is arranged at the forward end of the frame while rising from the side members 10 at a point adjacent the

rear end thereof, are parallel uprights 13 between which the shock former indicated generally at B, is arranged for use in a manner to be presently described.

The shock former is made up of a plurality of curved sections their normal position normally defining a split annulus or band having its adjacent ends slightly flared and spaced an appreciable distance apart as shown in Fig. 1 to provide an entrance for the sheaves as they are transmitted or conveyed from the binder (not shown). The intermediate section 15 of the former is terminally connected to the arms 16 which are mounted in the uprights 13. The corresponding end sections 15' of the former are carried by levers 17 which are freely pivoted upon the arms 16, a lug 18 projecting from each lever and reposing upon the adjacent arm 16, whereby the end sections 15' are supported normally in a position shown in Fig. 1. A link 19 provides a connection between one of the arms 16 and a manually operable lever 20 through the instrumentality of which component parts of the former are adjusted in the manner and for the purpose to be hereinafter described.

An endless conveyer 21 is mounted upon a support 22 which is carried by the frame A at one side thereof. An element 23 is suitably secured to one side of the binder B and projecting from said element are spaced eyes 24 adapted to align with the eyes 25 projecting from the support 22, pivot bolts 26 being passed through said eyes and providing a pivotal connection between the binder and the attachment. The opposite sides of the frame A are supported by one or more ground engaging wheels 27. The conveyer 21 may be operated in any suitable manner, but is utilized for conveying the sheaves from the binder to the shock former B.

If desired, the shock former may be provided with an end wall to maintain the ends of the sheaves straight, as the latter are deposited into the former B from the endless conveyer 21. As shown in this specific instance, the end wall comprises an arcuate shaped member 28 from which extends a plurality of spaced parallel tines 29. The end wall is associated with the end sections

15' of the shock former, through the instrumentality of the hooks 30 which engage one of a pair of spaced eyes 31 carried by the end sections 15'. The remaining eye of 5 each pair of eyes secured to the end sections 15 are utilized to support the end wall in proper relation to the shock former during the adjustment of the latter to release the shock therefrom.

10 In practice, the sheaves are placed upon the endless conveyer from the binder, and are conveyed in a horizontal position to the former B. The parts are normally disposed in the manner disclosed in Fig. 1 to receive 15 the sheaves. When the proper number of sheaves to form the shock have been placed in the former B, the lever 20 is swung upon its pivot in a forward direction thus moving the arms 16 to a vertical position, and 20 the sections 15 and 15' of the former to the position disclosed in Fig. 2. In this position of the former B the sheaves forming the shock are disposed vertically, and rest upon the tines 29 of the end wall, which now 25 occupies a horizontal position as shown. Upon further movement of the lever 20 in a forward direction, the arms 16 are swung to a horizontal position, moving the intermediate sections 15 to the position disclosed 30 in Fig. 3, which is exactly the reverse from the normal position of the section, and in which position the shock is released to permit the wheeled frame A to pass from beneath the shock thus depositing the latter in a vertical or upright position upon the 35 ground. During the final adjustment of the intermediate section 15, the rocker moves independently of the end sections 15' the lugs 18 coöperating with the upright 40 13 to check the movements of the end sections through the instrumentality of the wheel frame.

After the shock has been released from the former, and the end wall removed from 45 beneath the shock, the lever 20 is moved in a reverse direction to restore the movable parts of the attachment to normal position. Manifestly, during the return of the parts to normal position, the arms 16 engage the 50 lugs 18 so that the intermediate sections 15 and the end sections 15' of the former move as a unit from a horizontal to a vertical or receiving position.

In order that the adjustment of parts may 55 be effected from the seat of the driver, I make use of a substantially U-shaped element or yoke 32 which is journaled in suitable bearings 33 on the platform 12. One of the parallel limbs 35 of the yoke is ex- 60 tended through an eye 34 carried by the lever 20, while a manipulating rod 36 extends from the remaining limb of the yoke within reach of the driver of the binder. Manifestly, the movement imparted to the 65 yoke through the operating rod 36 is trans-

mitted to the lever 20, and the movable parts of the attachment adjusted accordingly.

While I have shown and described what I consider the preferred embodiment of the invention, I desire to have it understood that what is herein shown is merely illustrative, and that I do not limit myself to this exact construction, and arrangement, and that such changes may be resorted to 75 when desired as fall within the scope of what is claimed.

What I claim is:—

1. A machine of the class described comprising a portable frame, a shock former including a plurality of pivotally connected sections unitedly defining a split band, adapted to receive the sheaves horizontally, means adjusting said sections as a unit to a position whereby the shock is vertically 85 arranged, said means including a lever, means whereby certain sections of the band are limited in their movement in this direction, and the remaining section permitted to be further adjusted independently by said lever to release the shock, and means whereby the finally adjusted section automatically returns the remaining sections to normal position upon reverse movement of said lever and section. 95

2. A grain binder attachment comprising a portable frame, spaced parallel standards on said frame, arms pivoted on said standards, a shock former including a plurality of curved sections unitedly defining a split band, one of said sections being terminally secured to said arms, the remaining corresponding end sections being freely pivoted on said arms, means carried by said end sections and coöperating with said arms whereby said sections are normally maintained in proper relation to define said band, said band being normally disposed vertically to receive the sheaves in horizontal position, means for moving said arms to a position 110 whereby said sections of the band are simultaneously adjusted to arrange the shock vertically and means whereby the end sections remain stationary upon further adjustment of said arms to move the sections thereby 115 in a position to release said shock.

3. A grain binder attachment comprising a portable frame, spaced standards carried thereby, arms pivoted upon said standards, a shock former including an intermediate 120 curved section secured to said arms, and correspondingly curved end sections freely pivoted on said arms, means carried by the end sections for engagement with said arms whereby all of said sections are normally 125 maintained in a position to unitedly define a split band, arranged to receive the sheaves in horizontal position, a wall supported by the end sections and normally disposed vertically, means for adjusting said arms 130

whereby said sections are moved as a unit to a position to arrange the shock vertically and to position the wall horizontally beneath the shock, and said end sections co-
5 operating with said standards to remain stationary while said arms are further rejected to move the intermediate section to a position to release the shock.

4. In a machine of the class described comprising a portable frame, spaced parallel standards thereon, a shock former including an intermediate section and end sections, all of said sections being curved to unitedly define a split band, arms pivoted on said stand-
10 ard and terminally connected with said intermediate section, said end sections being freely pivoted on said arms, a lever for adjusting the intermediate section, means carried by the end sections and engaging said arms, whereby the said end sections will be moved in unison with the intermediate section to a predetermined position, and said means cooperating with the standards to permit a continued movement of the inter-
15 20 25

mediate section independently of the end sections.

5. A machine of the class described comprising a portable frame, standards rising therefrom, a shock former including an in-
30 termediate section and end sections, said sections being curved and unitedly defining a split band, horizontally disposed arms piv-
35 otally mounted on said standards, the intermediate section being terminally connected with said arms, levers freely pivoted on said arms, and supporting said end sections, means for reversing the position of said arms and the intermediate section, means carried by the end sections and normally re-
40 posing upon said arms whereby the end sections are moved in unison with the intermediate section upon adjustment of the arms to a vertical position, and said means

coöperating with the standards to permit the arms to be further adjusted independently 45 of the end sections.

6. A machine of the class described comprising a portable frame, spaced standards rising therefrom, arms pivoted on said standards and normally disposed in hori- 50 zontal position, a shock former including an intermediate section and end sections, said sections being curved and unitedly defining a split band, said intermediate section being terminally connected with said 55 arms, levers freely pivoted on said arms and supporting the end sections, a lug project-
ing from each lever and reposing upon said arms, whereby all of said sections are adjusted in unison upon movement of the arms 60 in an upward direction, means for reversing the position of said arms and the intermediate section, and said lugs being ar-
ranged to contact the said standards on a predetermined position of the end sections, 65 whereby the intermediate section can be further adjusted independently of the end sections.

7. A machine of the class described comprising a portable frame, a shock former in- 70 cluding an intermediate section and end sections unitedly defining a split band, said sections being pivotally mounted and as-
sociated whereby said sections may be moved in unison to a predetermined position, and 75 the intermediate section independently moved to its final adjusted position, an end wall associated with the end sections and normally disposed in a vertical position, and yieldable means supporting the end wall, 80 whereby the latter is permitted movement independently of the end sections and in a vertical plane subsequent to the adjustment of the end sections.

In testimony whereof I affix my signature. 85
ANDREW R. PETERSON.
